HEINRICH DEGENER, OF BERLIN, GERMANY, ASSIGNOR TO MERGENTHALER LINOTYPE COMPANY, A CORPORATION OF NEW YORK.

TYPGRAPHICAL COMPOSING AND LINE-CASTING MACHINE.

1,008,705.

Specification of Letters Patent. Patented Nov. 14, 1911.

Application filed August 25, 1911. Serial No. 646,013.

To all whom it may concern:

Be it known that I, HEINRICH DEGENER, a subject of the German Emperor, residing at 26 Hollmannstrasse, Berlin, in the German Empire, have invented new and useful Improvements in Typographical Composing and Line-Casting Machines, of which the following is a specification.

This invention relates to typographical 10 composing and line-casting machines such as those known commercially under the trade mark "Linotype," and particularly to those machines which are provided with circulating matrices each of which has two 15 formative cavities one above the other, and which matrices can be assembled with either of the said cavities in the composing line. In these machines there are devices already 20 known by which the descent of the matrices into the assembler elevator is arrested before the matrices reach their lowest position therein, and by which, during their advance along the said elevator, or during the ascent of the latter, the said matrices can be brought 25 into the lower position, by intervals or gaps in the matrix-supporting ledges.

According to the present invention the descent of the matrices is arrested by a stop which is so arranged that the said matrices 30 strike it at the middle part of their feet as distinguished from existing arrangements whereby their descent is arrested by their bottom lugs coming into contact with an adjustable ledge or stop; by these means much 35 wear, detrimental to good alinement of the matrices, is avoided.

In the accompanying drawing which shows the preferred constructional form of the invention, Figure 1 is a front elevation 40 partly in vertical section of the assembler elevator and other adjacent parts, and Fig. 2 is a plan partly in horizontal section of parts of Fig. 1.

The construction of the assembler elevator 45 1 and of the fixed ledge 2 and movable ledge 3 which hold the matrices in their different levels, corresponds with that of existing arrangements, with the exception that instead of the short stationary ledge which hitherto has been employed for stopping the 50 descent of the matrices a block 4 is arranged at the entrance end of the assembler elevator, between the two sides of the latter and not adjustable as to height. The mat-

rices 5 in their descent are all arrested by 55 this block 4 at the same height, and they contact with the block only with the middle part of their feet, the lugs involved in the subsequent alinement taking no active part in this actual stoppage. If the movable 60 ledge 3 is in the position shown in Fig. 2, that is to say with its right-hand end at a distance away from the block 4, the matrices on moving leftward off the block 4, will fall on to the lower ledge 2. If the matrices are 65 to remain in their upper position, the movable ledge 3 is pushed into its rightmost position, so that its right-hand end is flush with the right-hand end of the assembler 70 elevator. The top surface of the block 4 75 may be somewhat higher than the movable ledge 3, so that when the latter is in its last-named position, the matrices will not strike upon the ledge. When the matrices at the right-hand end of the line are to be retained in their upper position, it is necessary to move the ledge 3 into its rightmost position so that it will support those matrices during the upward movement of the assembler 80 elevator.

In order to prevent the matrices falling between the block 4 and the known star wheel 6, the block 4 may, with advantage be provided with a nose or rib 7, and the arms of the star wheel with corresponding 85 recesses 8 to clear the said rib, by which arrangement the block can extend well beneath the wheel 6 without interfering with its rotation.

The space-bars descending from their 90 magazine can as a rule, without difficulty, be assembled in line, their feet being beveled and the block 4 not projecting very far into the line. But in order to remove all possibility of the space-bars being interfered 95 with by the block 4 the latter may be movable in a horizontal direction, for which purpose it can be provided with a draw rod 9, which is guided in the machine frame and so operated by the space-bar escapement 100 mechanism that at each release of a space-bar the block 4 will be drawn rightward and, after the space-bar has taken up its proper place in the assembling line, returned to its normal position. The mechanism for withdrawing the block 4 as last described is not shown in the drawing, and it 105 may be of any desired construction.

Having thus described my invention, I declare that what I claim and desire to secure by Letters Patent is:—

1. In a typographical composing machine, 5 the assembler elevator provided with means to sustain the matrices at different levels, combined with a stop device, normally in operative position to arrest the descent of the matrices, said stop device being movably arranged to permit it to be shifted in the machine out of operative position to permit the space bands to enter the line without interference with the stop device.
- 10 2. In a typographical composing machine, 15 the assembler elevator provided with means

to sustain the matrices at different levels, combined with a stop, normally in position to arrest the descent of the matrices, the said stop being movably arranged to permit it to be shifted horizontally to an abnormal 20 position in the machine; whereby the space bands will be permitted to pass into the line without interference with the stop.

In witness whereof I have hereunto set my hand in the presence of two witnesses. 25

HEINRICH DEGENER.
